UNITED STATES PATENT OFFICE.

MURRAY SCHICK, OF SAN FRANCISCO, CALIFORNIA.

HAIR GUARD AND TEMPLATE.

Application filed April 6, 1925. Serial No. 20,946.

My invention relates to a combined hair-guard and template adapted for use in cutting or shaving the hair at the back of a person's neck. My template is designed to be attached to the back of the head with the band passing over the forehead, so that the wearer may himself trim or shave the hair at the back of his neck.

My template is preferably made of a thin sheet of celluloid or other suitable material which may readily be maintained in a sanitary condition, and when flattened forms substantially a segment of a flat ring. The device has a slit extending inwardly from each side edge sufficient to allow the guard to slightly bend or fold so as to adapt it to the shape of the head and a series of vertical slits are provided in the bottom edge so that the guard may follow the curvatures of the neck and outline the part to be shaved.

By using my device it is not necessary for a person to have either a single or a double mirror to aid him in shaving the back of the neck or trimming the hair in the back to the proper line, as it is only necessary to shave downwardly from the guard, practically operating by feel and not necessarily by sight.

My invention will be more readily understood from the following description in connection with the drawings in which—

Figure 1 is a developed view of my hair-guard and template when flattened.

Figure 2 is a back view showing the manner of the cord fitting on the back of a person's head.

Figure 3 is a side view showing the position of the cord in reference to the ears.

Figure 4 is a face view of a wearer of my guard showing the clip and cord to be fastened over the forehead.

The guard as a whole is indicated by the numeral 1 and the construction is illustrated in Figure 1. This guard consists of a piece of celluloid or other suitable material having a convex curve 2 on its top edge cut to a concave curve 3 on its lower edge and having slightly curved or straight side edges 4. The shape of the edge 3 may be altered, and in manufacturing the device I would indicate lines such as 5 and 6 to guide a purchaser in trimming the lower edge to secure the desired shape of trimming his hair that he wishes. It will be manifest that by altering the shape of the lower edge 3, a

different line will be formed at the back of the neck, giving a different shape trim. The lower end has a series of vertical slits 7 to allow the device to conform more accurately to the form of a person's head.

It is preferable to have slits 8 extending inwardly from each side to allow the device to curve or slightly overlap at the sides when shaped to a person's head.

I form eyelets 9 in the upper section 10 of the guard, and eyelets 11 in the lower section 12, through each of these pairs of eyelets is threaded a cord 13, this preferably has a knot 14 outside the eyelet 9 and passes on the front side of the guard as indicated by dotted lines at 15 and is threaded through the eye 11 to the back of the guard. One of the cords 13 preferably has a clip 16 made of metal, with an eye 17, to engage a knot 18 and a spring 19 to clamp the opposite cord.

My hair-guard and template is secured to the head as indicated in Figures 2, 3 and 4. It will be seen that pulling the cord causes the lower portion 12 to slide up underneath the ends of the upper part 10, or else this will make a slight fold which will follow along the line of the slits 8, as indicated by the dotted line 20.

The device is easily made to suit different sized heads, as it can be manufactured in large sizes and readily trimmed down to suit smaller heads or to fit children so that their hair may be readily trimmed.

The manner of use of my device is as follows:—If being used by a man to trim his own hair or shave the back of the neck, it will be placed over the head and secured as shown. The neck and lower end of the guard may then be lathered, and when the razor is drawn downwardly over the lower part of the template it can do no harm and will not cut until the razor engages the neck, when the hair may be trimmed to the proper line without the operator requiring a mirror. My device may also be readily used by women in trimming their hair at the back of the neck, especially those having bobbed hair. My device is also useful for enabling children's hair to be trimmed at home without taking them to the barber.

My invention may be considerably modified in detail to suit particular types of hair shaving or trimming and may be made to fasten to the head in a variety of ways.

For instance a guard or template may be

made of suitable sheet material to trim a person's beard, mustache, or side whiskers. This would have a cord or suitable fastening device so that the person could secure the 5 guard or template in the desired position and thereby trim the whiskers, mustache, etc., as above described. The device may also be used in connection with various implements now on the market for cutting or trimming one's own hair without the services of a barber. The template I have shown could be modified in shape to trim the hair to a proper line at the forehead, temples and around the ears.

10 I desire that the claims, where not drawn specifically, to the single device as shown, cover other guards or templates which may be used for any of the above mentioned purposes.

15 Having described my invention what I claim is:

1. A hair trimming template comprising in combination a sheet of material having an outline when flat of substantially a segment 25 of a flat ring, a plurality of slits extending inwardly from the lower edge of the template and a cord to secure the template to the back of a person's head with the slits against a person's neck.

20 2. A hair trimming template as claimed in claim 1, having the cords attached in two places to the template and adapted to shape the template when the cords are drawn tight to the shape of the back of a person's head.

25 3. A hair trimming template comprising in combination a sheet of material which when flat is somewhat the shape of a segment of a flat ring, a plurality of straight slits extending inwardly from the lower edge 10 of the sheet and a slit extending inwardly from each end of the sheet and means to secure the template to the back of a person's head with the straight slits adjacent the back of a person's neck.

45 4. A hair trimming template as claimed in claim 3 in which the means to secure the template to the back of a person's head com-

prises a pair of eyes in one part of the template, a cord passing through each eye and a fastening for each cord to another portion 50 of the template.

5. A hair trimming template as claimed in claim 3 in which the means to secure the template to the back of a person's head comprises a pair of eyelets at the upper side edges and the lower side edges above and below the slits from the ends and cords passing through each pair of eyes and said cords being knotted at the upper eyes to prevent their movement and being threaded through 60 the lower eyes and means to secure the cords over a person's forehead.

6. A hair guard and template, comprising in combination a sheet of material adapted to cover part of a person's head or face and form a guard for the hair thereon, said sheet being cut to form a template outlining the hair to be shaved or trimmed and a cord or the like to fasten said guard and template to a person's head, with a series of slits extending inward from the template edge, adapted 70 to conform to the shape of a person's head or face.

7. A sheet of material adapted to be fitted against the back of the head having means 75 associated therewith for holding the same in position and formed with slits along the bottom edge so as to follow the contour lines of the neck.

8. A sheet of material as defined in claim 7 80 in which lines are laid off adjacent the bottom edge allowing the user to shape the bottom edge by cutting the sheet along said lines.

9. A sheet of material adapted to be fitted 85 against the back of the head formed with horizontal slits extending thereinto from the side edges and flexible fastening means for the sheet guided around the forehead and engaging the side edges on opposite sides of 90 the slit so as to allow the margins of the slits to overlap for shaping the sheet.

In testimony whereof I affix my signature.
MURRAY SCHICK.
